Des. 223,951
Patented June 20, 1972

223,951

WALL SCONCE

Andrew J. Wentz, Jr., Hazlet Township, Monmouth
County, N.J. (P.O. Box 187, Holmdel, N.J. 07733)

Filed Aug. 24, 1970, Ser. No. 24,654

Term of patent 14 years

Int. Cl. D26—01

U.S. Cl. D48—2

FIG. 1

FIG. 2

FIG. 3

FIG. 1 is a front perspective view of a wall sconce showing my new design;

FIG. 2 is a front elevational view thereof; and

FIG. 3 is a side elevational view thereof.

I claim:

The ornamental design for a wall sconce, substantially as shown and described.
